REELING DEVICE

Frank J. Wood, Riverside, Ill., assignor to Goodman Manufacturing Company, Chicago, Ill., a corporation of Illinois

Application March 11, 1940, Serial No. 323,276

6 Claims. (Cl. 242—72)

This invention relates to improvements in reeling devices for use in coiling thin metal as it comes from a processing mill, and has as its principal objects to provide a new and improved expansible winding drum for a reel of the class described, of a novel and simplified form, so arranged as to be readily expanded or collapsed in a simplified manner, when it is desired to coil the metal, or to remove the coiled metal from the drum.

Heretofore, expansible winding drums have been commonly used for coiling thin metal. Expansion or collapse of these drums has been effected by various forms of linkage arrangements or by cam or wedge actions. These expanding mechanisms have all been relatively complicated with a number of wearing parts, and the effort necessary to expand or collapse the drum, especially with the cam and wedge type mechanisms, has been excessive. Due to space limitations, it has not been possible to provide adequate bearing area for the parts and construct them of sufficient size to withstand these excessive pressures and wear.

In my present invention I overcome these difficulties by providing a simplified form of expanding mechanism for a winding drum for coiling metal, which enables the parts to be of greater size and strength than with expansible winding drums heretofore used, and which also gains the advantage of rolling friction of the expanding parts against the usual sliding friction between these parts which is present in the reeling drums of this type now in use.

Other objects of my invention will appear from time to time as the following specification proceeds, and with reference to the accompanying drawings, wherein:

Figure 1 is a view in side elevation of a reel constructed in accordance with my invention;

Figure 2 is an end view of the reel shown in Figure 1;

Figure 3 is an enlarged detail view in side elevation of the reel, with certain parts broken away and certain other parts shown in longitudinal section;

Figure 4 is an enlarged sectional view taken substantially along line 4—4 of Figure 3;

Figure 5 is an enlarged sectional view taken substantially along the same lines as Figure 4, but showing the drum segments in a collapsed position;

Figure 6 is an enlarged sectional view taken substantially along line 6—6 of Figure 3;

Figure 7 is an enlarged end view of the drum

looking towards the free end thereof, with certain parts broken away and certain other parts shown in transverse section;

Figure 8 is a detail side view of a portion of the drum, drawn to substantially the same scale as Figure 3, showing the reel in a collapsed position, with certain parts broken away and in longitudinal section;

Figure 9 is a transverse sectional view taken substantially along line 9—9 of Figure 3; and

Figure 10 is a transverse sectional view taken substantially along line 10—10 of Figure 8.

In the embodiment of my invention illustrated in the drawings, the strip metal coming from the rolling mill, cleaning device or other processing mill, is wound on a winding drum 10 mounted on a shaft 11 overhanging a supporting framework 13. Said shaft is journaled in a bearing support member 12 mounted on said support

framework. Said bearing support member is of a relatively heavy construction, to support said drum and shaft in overhanging relation with respect thereto, so the coil of strip metal may be removed from the overhanging end there-

of. A suitable motor (not shown) is provided to drive said shaft and winding drum through a suitable drive connection which may be of any well known type. The strip material may be propelled to the reel in a suitable manner, such as a pair of pinch rolls, and may be formed to conform to the shape of the reel so it may be wound thereon by means of a suitable forming means, which may be the usual form of belt wrapper, or a plurality of rolls arranged to bend the metal to the form of said reel in a manner well known to those skilled in the art. Said forming mechanism is not herein shown or described since it forms no part of my present invention.

Referring now in particular to the details of the winding drum 10 and certain novel features of my invention, said winding drum consists of a drum segment 15, journaled on the shaft 11, and a plurality of expansible drum segments 17, 17, pivotally connected to opposite sides of said first

mentioned drum segment and forming a continuation of the periphery thereof, to provide a generally cylindrical drum, when said drum segments are in an expanded position.

The drum segment 15 is provided with bearing support members 16, 16 extending inwardly from opposite ends thereof, the inner ends of which are split in a plane extending through the center of the shaft, to form a means for journaling said drum segment on said shaft (see Figure 5). Said drum segment is likewise provided

with spaced apart inwardly projecting portions 18, 18, spaced inwardly from the ends thereof, which extend partially around outer rings 19, 19, of suitable anti-friction bearings for said shaft (see Figure 6).

The expansible drum segments 17, 17 are each provided with a plurality of spaced apart inwardly extending lugs 20, 20 extending inwardly from one side thereof. Said lugs are recessed within the bearing support members 16, 16 and the inwardly projecting portions 18, 18 of the drum segment 15. Rods 22, 22 extend through said lugs and said bearing support members and inwardly extending portions, to pivotally connect said expansible drum segments to opposite sides of the drum segment 15, in such a manner that the outer periphery of said expansible drum segments and the drum segment 15 will be generally in the form of a cylinder, when said expansible drum segments are in an expanded position.

The means for expanding the drum segments 11, 17 or permitting them to collapse includes a plurality of spaced apart eccentrics 23, 23, herein shown as being formed integral with the shaft 11. Annular rings 24, 24 encircle said eccentrics and the inner peripheries of said rings form inner races of anti-friction bearings between said eccentrics and annular rings. The bearings between said eccentrics and rings are herein shown as being needle bearings of a well known construction and include a plurality of hardened rollers of a small diameter interposed between said eccentrics and said rings (see Figure 6). The outer peripheries of the annular rings 24, 24 are adapted to engage spaced apart bearing shoes 26, 26 on the inside of an expanding member 27. Said expanding member extends along said winding drum for substantially the entire length thereof, and is disposed between adjacent free sides of the drum segments 17, 17. Oppositely facing inclined sides 28, 28 are provided on said expanding member which are adapted to engage inclined sides on adjacent ends of said movable drum segments, so that rectilinear movement of said expanding member in an outward direction will cause said expansible drum segments to pivot outwardly about the axes of the rods 22, 22.

Thus, a rolling anti-friction connection is provided between said eccentrics and expanding member, to minimize frictional resistance between said eccentrics and expanding member, so that when the drum segment 15 is held from rotation and the shaft 11 continues to rotate, the eccentrics 23, 23 and annular rings 24, 24 will cause the expanding member 27 to move in an outward direction and pivot said expansible drum segments outwardly to an expanded condition. Said eccentrics are so arranged that 180 degrees of rotation thereof with respect to the drum segment 15 will fully expand the drum from a collapsed condition, and the same amount of rotation of said shaft with respect to said drum will permit said drum to be fully collapsed.

Yieldable means are provided to move the expanding member 27 inwardly towards the center of the winding drum 10, as the eccentrics 23, 23 are moved in a direction to permit the drum segments 17, 17 to collapse. As herein shown, said means includes a plurality of spaced apart yokes 30, 30 secured to the inner side of said expanding member in a suitable manner, such as welding. Corresponding yokes 31, 31 are journaled on the shaft 11 and are connected to the yokes 30, 30 by means of connecting rods 32, 32 extending

through opposite ends of said yokes. Said expanding member is urged towards the shaft 11 by means of compression springs 33, 33 encircling said rods and interposed between opposite outer sides of the yokes 31, 31 and collars 34, 34, secured to the outer ends of said rods. Nuts 35, 35, threaded on said rods, abut the outer sides of the yokes 30, 30, to hold said rods to said yokes and to provide a means for adjusting said springs.

The drum segments 17, 17 are collapsed, as the expanding member 27 moves inwardly towards the shaft 11, by means of spaced apart tension springs 36 and 37 (see Figures 2, 3 and 7). The tension spring 36 is mounted at the end of said drum adjacent the bearing support member 12 and has connection at its opposite ends with said movable drum segments, adjacent the free ends thereof (see Figure 7). The tension spring 37 is mounted at the opposite end of said drum segments and is connected thereto at its opposite ends, adjacent the free ends thereof (see Figure 2). Said springs thus tend to hold said drum segments in engagement with the inclined sides 28 of the expanding member 27 and move said drum segments to a collapsed condition as said expanding member moves towards the shaft 11.

A clutch member 40 is provided to drive the winding drum 10 from the shaft 11. Said clutch member is feathered on said shaft and is provided with jaws 41 and 42 at opposite sides thereof, either one of which may have driving engagement with a jaw 43 on the drum segment 15 (see Figures 3, 8, 9 and 10). The jaw 42 is of a greater depth than the jaw 41 so that when the clutch member 40 is moved away from the drum segment 15 to disengage the jaw 41 from the jaw 43, the shaft 11 may rotate with respect to said drum until the jaw 42 engages the jaw 43. The jaw 42, however, can never be moved to a position to pass by the jaw 43. Rotation of said shaft with respect to said drum, when the jaw 41 is disengaged from the jaw 43 and said drum is held from rotation, as herein shown is 180 degrees and is sufficient to completely expand, or permit the drum segments 17, 17 to be completely collapsed. It should here be noted that since the jaw 42 can never clear the jaw 43, that when it is desired to collapse the drum, the direction of rotation of the shaft 11 must be reversed.

A friction band 45 is provided to engage the drum segment 15 and hold said drum segment from rotation, when the jaw 41 is disengaged from the jaw 43. As herein shown, said friction band is secured to the supporting framework 13 at one of its ends by means of a pin 46. Said friction band extends over the drum segment 15 and engages the outer periphery of a flanged member 47 projecting from the end thereof adjacent the clutch member 40. The opposite end of said friction band has connection with a cable 49, which serves to engage said band with said braking surface and hold said drum segment from rotation. The cable 49 is trained downwardly from said friction band, under a sheave 50, and inwardly to a lever 51, to which said cable is secured. A sheave 53 is mounted on a shaft 52 which also has said lever mounted thereon. Said sheave is adapted to rotate said shaft and rock said lever. A cable 54 is trained under said sheave and is secured at one of its ends to a lever arm 55 of a pedal or foot lever 56, mounted on a bracket 57. Said cable extends upwardly from the sheave 53 over a sheave 59

and outwardly therefrom, and is connected at its ends to a connecting member 60 on the inner end of a rod 61. Said rod is slidably guided in an I-beam 63, which forms a part of the supporting framework 13, and is provided with a bifurcated outer end 64, which is pivotally connected to a yoke 65, pivoted to a bracket 66 projecting from said supporting framework. A compression spring 67 encircles said rod and is interposed between said I-beam and the bifurcated end of said rod, and urges said rod in a direction to cause said yoke to move said clutch member to an engaged position.

It may be seen from the foregoing that when the foot lever 56 is depressed, the clutch member 40 will be moved in a position to permit the jaw 41 to be disengaged from the jaw 43. At the same time, the friction band 45 will engage the drum segment 15, to hold it from rotation. When said drum is held from rotation, the shaft 11 will rotate with respect thereto until the jaw 42 engages the jaw 43. During this time the expandable drum segments 17, 17 may be moved from a collapsed to a fully expanded position. Upon engagement of the jaw 42 with the jaw 43 and the release of pressure from said foot lever, the winding drum 10 will continue to rotate in the same manner as formerly.

When it is desired to collapse the drum segments 17, 17, the direction of rotation of the shaft 11 is reversed and the foot lever 56 is depressed, to hold the drum segment 15 from rotation and to disengage the jaw 41 from the jaw 43. This permits the shaft 11 to rotate 180 degrees with respect to the drum segment 15 at which time the jaw 42 will engage the jaw 43 and the eccentrics 23, 23 and annular rings 24, 24 will have moved the expanding member a distance sufficient to permit the tension springs 36 and 37 to fully collapse said drum segments.

It may thus be seen that a simplified form of expandable winding drum for sheet metal has been provided which is so arranged that the drum may be expanded or collapsed through a simple form of mechanism, by simply holding the drum segment 15 from rotation and permitting the shaft 11 to rotate 180 degrees with respect thereto, that this mechanism permits the use of relatively large heavy parts, and that rolling friction in place of sliding friction effects the expansion of the drum.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a reel for strip metal, a shaft, an expandable drum mounted on said shaft including a drum segment journaled on said shaft, a connection for driving said drum segment from said shaft, expandable drum segments forming continuations of said first mentioned drum segment, said expandable segments being pivotally connected to opposite sides of said first mentioned drum segment, for movement about axes parallel to the axis of rotation of said drum segment, and means for expanding said drum segments in a direction to form a generally cylindrical drum including means for holding said drum segment from rotation while said shaft continues to rotate, an eccentric on said shaft, a

wedge-shaped expanding member engaging adjacent ends of said expandable drum segments, and an operative connection between said eccentric and expanding member including an anti-friction bearing, the outer periphery of the outer race of which is adapted to engage said expanding member.

2. In a reel for strip metal, a shaft, an expandable drum mounted on said shaft including a drum segment journaled on said shaft, expandable drum segments pivotally connected to opposite ends of said first mentioned drum segment and forming continuations thereof, and means for pivoting said drum segments in an outward direction, to form a generally cylindrical drum including an expanding member engaging adjacent ends of said movable drum segments, a member journaled on said shaft eccentric of the center thereof and engaging said expanding member, means for holding said drum from rotation, and a drive connection from said shaft to said first mentioned drum segment, said drive connection including means for selectively permitting rotation of said shaft with respect to said drum a predetermined distance and rotating said shaft and drum together beyond this distance, for causing said eccentrically mounted member to move said expanding member outwardly from the center of said drum and pivotally move said drum segments in an outward direction, to an expanded position.

3. In a reel for strip metal, a shaft, an expandable drum mounted on said shaft including a drum segment journaled on said shaft, expandable drum segments pivotally connected to opposite ends of said first mentioned drum segment and forming continuations thereof, and means for pivoting said drum segments in an outward direction, to form a generally cylindrical drum including an expanding member engaging adjacent ends of said movable drum segments, an annular ring journaled on said shaft eccentric of the center thereof and having engaging connection with said expanding member for moving said expanding member outwardly with respect to said shaft upon relative movement of said shaft with respect to said drum, a friction band adapted to engage said drum and hold it from rotation, a clutch member for driving said drum from said shaft, said clutch member being adapted to disconnect said drum from said shaft to permit said shaft to rotate a predetermined amount with respect to said drum, when said drum is held from rotation, but to rotate said drum with said shaft after said predetermined free rotation of said shaft, to cause expansion of said drum without stopping rotation of said shaft.

4. In a reel for strip metal, a shaft, an expandable drum mounted on said shaft including a drum segment journaled on said shaft, expandable drum segments pivotally connected to opposite ends of said first mentioned drum segment and forming continuations thereof, and means for pivoting said drum segments in an outward direction, to form a generally cylindrical drum including an expanding member engaging adjacent ends of said movable drum segments, an annular ring journaled on said shaft eccentric of the center thereof and having engaging connection with said expanding member for moving said expanding member outwardly with respect to said shaft upon relative movement of said shaft with respect to said drum, a friction band adapted to engage said drum and hold it from rotation, a clutch member for driving said drum from said shaft,

said clutch member being adapted to disconnect said drum from said shaft, to permit said shaft to rotate a predetermined amount with respect to said drum, when said drum is held from rotation, but to rotate said drum with said shaft after said predetermined free rotation of said shaft, to cause expansion of said drum without stopping rotation of said shaft, and common operating means for said clutch and brake band for simultaneously disengaging said clutch and applying said brake.

5. In a reel for strip metal, a shaft, an expandable drum mounted on said shaft including a drum segment journaled on said shaft, expandable drum segments pivotally connected to opposite ends of said first mentioned drum segment and forming continuations thereof, and means for pivoting said drum segments in an outward direction, to form a generally cylindrical drum including an expanding member engaging adjacent ends of said movable drum segments, an annular ring journaled on said shaft eccentric of the center thereof and having engaging connection with said expanding member for moving said expanding member outwardly with respect to said drum, yieldable means for holding said engaging member in engagement with said annular ring and other yieldable means connected between the free ends of said expandable drum segments, for holding said drum segments in engagement with said expanding member and collapsing said drum segments upon movement of said expanding member towards the axis of rotation of said drum.

6. In a reel for strip metal, a shaft, an expand-

sible drum mounted on said shaft including a drum segment journaled on said shaft, expandable drum segments pivotally connected to opposite ends of said first mentioned drum segment and forming continuations thereof, and means for pivoting said drum segments in an outward direction, to form a generally cylindrical drum including an expanding member engaging adjacent ends of said movable drum segments, an annular ring journaled on said shaft eccentric of the center thereof and having engaging connection with said expanding member for moving said expanding member outwardly with respect to said shaft upon relative movement of said shaft with respect to said drum, yieldable means for holding said engaging member in engagement with said annular ring, other yieldable means connected between the free ends of said expandable drum segments, for holding said drum segments in engagement with said expanding member and collapsing said drum segments upon movement of said expanding member towards the axis of rotation of said drum, a friction band adapted to hold said drum from rotation, a clutch member for driving said drum from said shaft, said clutch member being arranged to disconnect said drum from said shaft, to permit a predetermined rotation of said shaft with respect to said drum, but to rotate said drum with said shaft after said predetermined period of free rotation of said shaft, to cause expansion of said drum upon rotation of said shaft in one direction and retraction of said drum upon rotation of said shaft in an opposite direction.

FRANK J. WOOD.
